UNITED STATES PATENT OFFICE

162,038

EGG COOKER

Ivar Jepson, Oak Park, Ill., assignor to Sunbeam Corporation, Chicago, Ill., a corporation of Illinois

Application January 7, 1950, Serial No. 7,070

Term of patent 14 years

(Cl. D44—1)

To all whom it may concern:

Be it known that I, Ivar Jepson, a citizen of the United States, residing at Oak Park, in the county of Cook, and State of Illinois, have invented a new, original, and ornamental Design for an Egg Cooker, of which the following is a specification, reference being had to the accompanying drawing, forming part thereof.

In the drawings:

Figure 1 is a top plan of an egg cooker embodying my new design;

Figures 2 and 3 are side elevational views thereof, showing the cooker rotated ninety degrees with respect to each other.

I claim:

The ornamental design for an egg cooker, substantially as shown.

IVAR JEPSON.
